UNITED STATES PATENT OFFICE.

GEORGE EDMUND DOUGHTY, OF CALDWELL, NEW JERSEY.

MANIFOLDING SALES-BOOK.

1,153,611.

Specification of Letters Patent. Patented Sept. 14, 1915.

Application filed April 24, 1913. Serial No. 763,193.

To all whom it may concern:

Be it known that I, GEORGE E. DOUGHTY, a citizen of the United States, residing at Caldwell, in the county of Essex and State of New Jersey, have invented certain new and useful Improvements in Manifolding Sales-Books, of which the following is a full, clear, and exact description, such as will enable others skilled in the art to which it appertains to make and use the same.

This invention relates to manifolding sales books; and with regard to certain more specific features thereof, to manifolding sales books and the like of the triplicate type.

One of the objects of the present invention is to provide a practical device of the above nature adapted to form a plurality of clear and legible copies of any transaction made thereon.

Another object is to provide a durable device of the above character in which the leaves may be rapidly and efficiently manipulated without soiling the fingers by contact with the manifolding materials.

A further object is to provide a simple form of multiplicate sales book which shall be cheap to manufacture, rapid and efficient in manipulation.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawing wherein is shown one of the various possible embodiments of this invention, Figure 1 is a perspective view showing a sales book in normal operative position; Fig. 2 is a diagrammatic side elevation of the sales book; Fig. 3 is an enlarged detail view showing the manner of cutting the several leaves and carbon sheets; and Fig. 4 is a similar view with the upper leaves removed.

Similar reference characters refer to similar parts throughout the several views of the drawing.

Referring now in detail to the accompanying drawing, and more particularly to Fig. 1, a main support or holder 1 has flexibly connected therewith by means of a hinge 2 a top cover 3 which is adapted to be folded

over when the book is not in use. Along the bottom transverse edge of the support is mounted or secured a suitable form of pad-retaining device 4 adapted to clamp the stub portion of a pad 5. This pad 5 is of the paragon type, being composed of a set of sheets each of which is folded so as to provide original and duplicate leaves, the duplicate leaves being at one end connected to the support through their stub portions 6 by means of the holder 4. At the opposite transverse edge of the support 1 in the present form is a second pad-holding and connecting device 7 adapted to hold a second pad 8 comprising a plurality, or set of single leaves hereinafter referred to as triplicate leaves. Each of these pads is thus independently connected to the support and has associated therewith suitable manifolding means, preferably in the form of transfer sheets such as single-faced carbon sheets, one of which, 10, is bound with the leaves of the pad 5 and thereby joined to the support 1, substantially at the connected portion of the folded sheets and is adapted to occupy a normal operative position between the original and duplicate leaves of each set as they are successively used. A second transfer sheet, such as a single-faced carbon sheet 11 is secured with the leaves of the triplicate pad, or other set of leaves by means of the holder 7.

As shown more clearly in Fig. 2, an original leaf 12 upon which the inscription is made rests above the carbon sheet 10 which, in turn, is positioned above the duplicate portion 13 of the top set of leaves of the pad 5. Immediately beneath or on the opposite side of this duplicate leaf 13 is positioned the carbon sheet 11 which will transfer the inscription to the top leaf 14 of the pad 8. It will thus be seen that when the pad is in normal operative position, as shown in Fig. 1, three clear and distinct copies of any transaction will be reproduced by the present device. The body portions of these pads normally overlie one another with the effective portions of the leaves in registry, the sheets of each set extending from their respective connected portions toward the connected portion of the other set, one setlapping the other. This arrangement permits the leaves of either set to be withdrawn from lapping relation with ease and rapidity, and permits the leaves of the lower set to be withdrawn from beneath the upper

set without disturbing said upper set. Furthermore it will be noted that the lines of folds of the folded sheets lie at a distance from the connected portion of the other set of sheets, being not close enough to said connected portion to require an abrupt bend in the set of single sheets, when the latter lies above the other set. Also it will be observed that the edges of the folded sheets 10 opposite their connected portions are free, and lie in a transverse plane between their connected portion and the free ends of the set of single sheets, so that the free ends of the folded sheets may be readily grasped, 15 either through the cutaway portion (hereinafter referred to) of the carbon sheet 10, or when said carbon sheet is thrown back.

Contributing to the general efficiency of the sales book and in order to aid in its rapid 20 manipulation, the various leaves of each set and the associated carbon sheets are cut in the manner shown in Figs. 3 and 4, in order that the book may be handled without soiling the fingers by contact with the manifolding means. Fig. 3 shows the lower right hand corner of the original leaf 12 turned back to show more clearly the cut-away portion of the carbon sheet 10, which cutaway portion is positioned opposite the free ends 25 of the folded sheets, being above the duplicate leaf 13 when in operative position. This cut-away portion will permit the operator to grasp the corner of the original leaf of the next set after completing the 30 transaction and removing the top set of leaves upon which the inscription has been made. From Fig. 4 it will also be noted that the lower right hand corner of the carbon sheet 11 is cut away as indicated at 16, 35 in order that the diagonally cut corner 17 of the triplicate leaf 14 may be more conveniently grasped. It will of course be understood that the leaves of the pads are provided with lines of perforations 20, 21 40 in order that they may be conveniently severed from each other and the stub portions retained by the holding clamps. The leaves are also provided with ruled spaces and printed matter as may be desired, in 45 order to more efficiently accomplish the purpose or use for which they are intended.

The operation and method of use of a sales book of this character is substantially as follows: Assuming the book to be in operative position, as shown in Fig. 1, and the recording of the transaction completed, the 50 lower right hand corner of the original sheet 12 is grasped by the operator and moved upwardly and rearwardly. This will automatically withdraw the carbon sheet 10 there-beneath and cause the same to fall toward the operator. The set of leaves is then severed along the dotted lines 21 and the two parts separated and disposed according to the rules of the establishment.

With the book in this position access to the corner 17, Fig. 4, of the triplicate leaf 14 is more easily obtained. This corner is grasped and the top triplicate leaf torn from the stub, which operation may be accomplished without disturbing the carbon sheet 11. The free end of the next original leaf 12 is then grasped by the operator in one hand, and pulled toward the operator, the original and duplicate leaf being thus drawn from beneath the set of triplicate leaves without substantially moving said set, and the withdrawn folded sheet is then permitted to fall onto the carbon 11, the other hand of the operator swinging the carbon sheet 10 into position between the original and duplicate leaves as they are permitted to fall onto the leaves of the other set. The book is then again in operative position ready for recording.

It will thus be seen that the present invention provides a book in which the leaves may be rapidly and efficiently manipulated, the carbon sheets almost automatically falling into their proper operative position. The book is simple and practical in its construction, is cheap to manufacture and accomplishes, among others, all the objects and advantages above set forth.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. A manifolding device comprising, in combination, a support, two sets of record sheets, one end of each of said sets connected to said support along lines spaced apart on said support, the opposite end of each set being free and lapping a portion of the other set, the under pad composed of folded sheets each providing an original and a duplicate leaf, and two transfer sheets carried by said support and adapted to be disposed one between an original and a duplicate leaf and the other between a duplicate leaf and the other set of sheets, when in operative position.

2. A manifolding device comprising, in combination, a support, two sets of record sheets, one end of each of said sets connected to said support along lines spaced apart on said support, the opposite end of each set being free and lapping a portion of the other set, the under pad composed of folded sheets each providing a duplicate and an original leaf, and two transfer sheets carried by said support and adapted to be dis-

posed one between an original and a duplicate leaf and the other between a duplicate leaf and the other set of sheets, when in operative position, said transfer sheets being 5 respectively connected to said support along the lines of connection of said respective sets with said support.

3. A manifolding device comprising, in combination, a support, two sets of record 10 sheets, one end of each of said sets connected to said support along lines spaced apart on said support, the opposite end of each set being free and lapping a portion of the other set, the under pad composed of folded sheets 15 each providing an original and a duplicate leaf, the free ends of said original leaves lying between said line of connection of the folded sheets and the free end of the other set of sheets, and two transfer sheets carried 20 by said support and adapted to be disposed one between an original and a duplicate leaf and the other between a duplicate leaf and the other set of sheets, when in operative position.

25 4. A manifolding device comprising, in combination, a support, two sets of record sheets, one end of each of said sets connected to said support along lines spaced apart on said support, the opposite end of each set 30 being free and lapping a portion of the other set, the under pad composed of folded sheets each providing an original and a duplicate

leaf, the lines of fold of said folded sheets lying at a distance from said line of connection of said other set of sheets, and two 35 transfer sheets carried by said support and adapted to be disposed one between an original and a duplicate leaf and the other between a duplicate leaf and the other set of sheets, when in operative position. 40

5. A manifolding device comprising, in combination, a support, two sets of record sheets, one end of each of said sets connected to said support along lines spaced apart on said support, the opposite end of each set 45 being free and lapping a portion of the other set, the under pad composed of folded sheets each providing an original and a duplicate leaf, the lines of fold of said folded sheets lying at a distance from said line of connection of said other set of sheets, the free ends 50 of said original leaves lying between said line of connection of the folded sheets and the free end of the other set of sheets, and two transfer sheets respectively connected at 55 one end thereof to said sets and therewith to said support.

In testimony whereof I affix my signature, in the presence of two witnesses.

GEORGE EDMUND DOUGHTY.
